UNITED STATES PATENT OFFICE.

HENRY W. ANSELL, OF STEGI, SWAZILAND, SOUTH AFRICA.

TOOTH-PASTE HOLDER.

Application filed August 7, 1926. Serial No. 127,964.

This invention relates to an improved tooth paste container and has for its object the production of a simple and efficient box which is especially designed to hold a tablet or block 5 of tooth paste.

One of the principal objects of this invention is the production of a simple and efficient box in which a tablet or other block of paste may be carried of a solid or semi-solid mass 10 for the purpose of permitting the bristles of the tooth brush to be moved backwardly and forwardly across the face of the block for the purpose of picking up particles of the paste.

A further object of this invention is the 15 production of a simple and efficient means for supporting the block of tooth paste and also for covering the top of the box when the paste is not in use.

Other objects and advantages of the present 20 invention will appear throughout the following specification and claim.

In the drawings, Figure 1 is a side elevation of the box,

Figure 2 is a top plan view thereof,

Figure 3 is a section taken on line 3—3 of Figure 2,

Figure 4 is a section taken on line 4—4 of Figure 3, and

Figure 5 is an end elevation of the under 30 portion of the box within which the block of tooth paste is positioned.

By referring to the drawings, it will be seen that 1 designates the bottom or base of the box which is preferably formed of a rectangular structure having upwardly extending sides 2, the inner faces of which are extended vertically to constitute a trough-like structure indicated particularly by the numeral 3. The ends of the walls 4 of the box terminate short 40 of the upper edges of the side walls 2 as clearly illustrated in Figure 3 and constitute shallow abutments 5, in which the respective ends of the tooth paste block are adapted to rest, in this way being held against longitudinal 45 movement within the base 1. Through the medium of the shallow or comparatively short end walls 4, it will be seen that a free longitudinal movement of a tooth brush will be permitted upon the tooth paste block which

50 is mounted within the trough 3 and in this way, will permit the block to wear down considerably in order to permit the maximum use of the block before the same is replaced by a new or refilling block. The vertical side walls 55 2 are adapted to extend throughout the nor-

mal height of the block and prevent the block from having lateral displacement upon the base 1. The outer faces of the end walls 4 as well as the outer edges or end edges of the side walls 3 are curved outwardly as indicated at 60 6 and the outer edges or sides of the side walls 3 are also curved outwardly as indicated at 7, to facilitate the placing and fitting of the outwardly flared ends and sides indicated by the numerals 8 and 9 respectively, of the cover 10 over the base 1. The cover 10 is provided with overhanging edges 11 to facilitate the removal of the cover 10 from the base 1 when it is desired.

From the foregoing description and by 70 carefully considering the drawings, it will be seen that a very simple and efficient box-like structure has been produced, which is flared at the bottom and tapers toward the top thereof to facilitate the placing of the cover 75 upon the box and also facilitate the holding of the box in proper position while rubbing the tooth brush upon the tooth paste which is placed within the base 1. It should be understood that in connection with the present invention it is desired to use a solid or semi-solid mass of tooth paste formed in a block-like structure of a rectangular form placed within the base, which block-like structure may be reduced from time to time as the 80 paste is used up. It is also desired to construct the box of aluminum, glass, earthenware, or china, without departing from the spirit of the invention. It should also be understood that certain detail changes in the 85 mechanical structure may be employed without departing from the spirit of the invention. It is to be further understood that the name of the firm furnishing the box may be embossed or otherwise placed upon the cover 90 as an advertising medium. The box is especially adapted for the purpose of maintaining the tooth paste in a solid and protected condition during shipment, and may be packed away with other articles without fear 95 of becoming injured or distorted in shipment as is now the case with tubes and boxes within which tooth paste is quite commonly used.

Since the dentifrice in the holder is solid or semisolid, the dentifrice will not be likely to leak or spill out of the container. In this way, the clothes will not be likely to become soiled when packed in a suit case or other container with the tooth paste holder.

Having described the invention, what is claimed is:

- As a new article of manufacture, a holder for a tooth cleaning material comprising a body having a flat bottom wall, upwardly extending relatively high longitudinal side walls and relatively short end walls terminating adjacent to the bottom wall constituting abutments, the said short walls permitting a free movement of a brush longitudinally of the tooth cleaning material across the entire

face thereof, the side and end walls being tapered toward their upper ends, and a cover having outwardly flared side and end walls for fitting snugly over the side and end walls of the body and constituting a seal therefor, the cover being provided with a laterally extending rim around the upper edge thereof for facilitating the removal of the cover from the body. 15 20

In testimony whereof I affix my signature.
HENRY W. ANSELL.
